Specification of Letters Patent.

Patented May 6, 1919.

Application filed April 23, 1915. Serial No. 23,306.

To all whom it may concern:

Be it known that I, ARTHUR PENTECOST, a subject of the King of England, residing at East Orange, Essex county, New Jersey, have invented new and useful Improvements in Adding-Machines, of which the following is a specification.

This invention relates more particularly to transfer or carrying mechanisms for adding machines.

Adding machines include a series of counters or accumulators, drive members therefor, normally set transfer devices controlled by the counters, and an actuating mechanism, which also operates a transfer resetting mechanism. The speed at which the machine can be operated, depends to a great extent upon the ability of the transfer devices to operate and the rapidity of their operation, it being necessary to reset the tripped transfer devices after one accumulating operation before further amounts are accumulated.

The normally set transfer devices may be tripped by the counters either during or after the completion of the return stroke of the actuating mechanism. The resetting mechanism, in general, has been devised for operation at the beginning of the forward stroke of the actuating mechanism, and because the resetting mechanism, when in operation, locks the transfer devices, it follows that the carrying operations started on a return stroke must be completed before the beginning of the next stroke.

The time interval between strokes is very short, especially in repeat operations of the machine, and to afford time for the carrying operation, it has been proposed to place the actuating mechanism under the control of the carrying devices to lock the actuating mechanism against operation during the carrying operation.

This is very objectionable because it prevents rapidly successive operations of the machine.

Objects of this invention are to provide for a more rapid operation of adding machines, and prolong the time within which the carry may take place on rapidly successive machine operations.

Another object is to render the action of the machine more easy and uniform, thereby

reducing the power necessary for its operation.

A further object is to improve and simplify the carrying or transfer mechanism and to reduce the necessity for adjustments, thereby decreasing the time employed in assembling the parts.

These objects I attain by extending the time within which the carrying may take place, into the succeeding stroke or operation of the actuating mechanism, and in effecting this result, I have deferred the actuation of the transfer resetting mechanism until just prior to the accumulation of further amounts.

It will be understood that while this invention is especially adapted for rapid operations, its advantages are also obtained in slow operations, although the necessity for utilizing the succeeding stroke for the completion of a carry is not then present.

Other objects and advantages will be more fully disclosed hereinafter and particularly pointed out in the claims.

In the accompanying drawings, Figure 1 is a side view of the well known Wales machine equipped with one embodiment of the invention, parts being omitted to better disclose the invention, which is illustrated in its normal idle position.

Fig. 2 is a longitudinal sectional view, showing the positions of the parts at the end of the forward stroke in an adding operation.

Fig. 3 is a similar view, showing the positions of the parts on the return stroke just before the tripping of the transfer devices.

Fig. 4 is a detail view, showing the positions assumed by the transfer devices when the carry has been completed.

Fig. 5 is a detail front view, and

Fig. 6 is a perspective detail of the resetting mechanism.

The invention will be described as applied to a Wales machine, although its use is not restricted thereto; and attention is directed to U. S. patents to McFarland and Wales, #880,157, February 25, 1908; Bickford, #1,069,104, August 5, 1913; and Wilgus, 1,133,596, Mar. 30, 1915, for a further understanding of the Wales mechanisms and operations hereinafter referred to.

Referring to Fig. 1, the base 965 supports

side frames 967, (one only of which is shown), between which are mounted the keyboard or indexing section, and the accumulating section, including the transfer or carrying mechanism.

The amount to be accumulated is set up on the keyboard, depression of the keys 190 of which (Fig. 2) rock levers 116 pivoted at 111, to project index pins or stops 115 into the paths of the adding racks or counter drive members 310 to determine the advance of the latter. The stops 115 displace rack detents 221 journaled on a cross shaft 202 which detents normally lie in the paths 15 of the drive members to prevent effective operations thereof.

The drive members are pivotally supported at 316 3/4 and 350 on front and rear arms 312 and 311 journaled on a cross shaft 200 and a cross rod 301, respectively.

Counters or accumulators 490 journaled on an axle 400 have pinions 435 adapted to mesh with the drive members 310. Arms 322 pivoted at 952 1/2 to the side frames 967 support the axle 400, and props 319 pivotally connected at 375 to the arms, rest upon a trip rod 303 and normally maintain the counters 490 and the pinions 435 out of engagement with the drive members 310.

Radius links 323 journaled on the cross shaft 300, sustain the trip rod, and draft bars 214 connect the trip rod 303 with cranks 210, 212 secured to the main drive shaft or prime mover 200, which effects the engagement and disengagement of the counters and drive members.

Springs 383 connected to the rear rack supporting arms 311 and to a restraining and restoring bar 205 mounted in a swinging frame 265 journaled at 261 1/2 in the side frames 967, tend to advance the drive members. Such advance is, however, normally prevented by an arm 210^a on crank 210, which arm carries a projection 241 seated in one end of a cam slot 220^a in an arm 220 secured to the frame 265, to lock the restraining and restoring bar 205 in the paths of the front rack supporting arms 312.

Turning the main drive shaft 200 (Fig. 2) by a handle 210 1/2, for instance, rocks the arm 210^a to cause the projection 241 to traverse the cam slot 220^a to rock the arm 220 and frame 265, which withdraws the restraining and restoring bar 205 and further tensions springs 383 to advance the drive members until they are arrested by the projected stops 115, or the detents 221 in those rows where no stops have been projected.

Turning the prime mover 200 also rocks the cranks 210, 212 which advance the draft bars 214 to swing the trip rod 303 forwardly in a descending arc, which lowers the props 319 and drops the counters toward their drive members. Legs 316 secured to the

counter axle 400 have feet 316^a which contact steps 958 1/2 on the side frames to arrest the descent of the counters to maintain the counters 490 disengaged from the drive members 310 until the latter have had time 70 to advance against the stops 115. This preliminary drop of the counters is of no significance, and merely takes up the safety clearance between the feet 316^a and the rests 958 1/2.

The trip rod 303 travels in slots 321^a in bridle or trip links 321 pivoted at 360 to the legs, the lower ends of the props 319 also being slotted, as at 319^a, to accommodate the trip rod, and consequently, after effecting 80 the slight preliminary descent of the counters, the further travel of the trip rod relatively to the counter shifting mechanism is idle in the slots 321^a and 319^a, until, as the main drive shaft approaches the end of its 85 forward stroke, the trip rod strikes the outer ends of the slots 321^a and displaces the legs 316 from the steps or rests 958 1/2, whereupon the axle 400 with its counters 490 drops to engage the latter, through the pinions 435, with the racks or drive members 310. Springs 380 connecting the props 319 and the trip rod facilitate such engagement.

The main drive shaft now at the end of its forward stroke, is released to the action 95 of the main restoring spring 285, which returns the shaft and connected parts to normal idle position. At the outset of such return, the arm 210^a of the crank 210 fast on the main drive shaft reverses its direction of travel in the cam slot 220^a, rocking the frame 265 to force the restraining and restoring bar 205 against the advanced front arms 312 of the drive members 310 to restore the members to normal retracted position. As the drive members retire, they turn the counters 490 to register thereon an amount corresponding to that set up on the keyboard.

While the drive members are being re-tired the trip rod 303 is idly traversing the slots 321^a and 319^a in trip links 321, and props 319 toward its normal position, to permit the registration of the amount on the counters. Just as the drive 110 members 310 have completed their effective return strokes, and when the main drive shaft is approaching its initial or home position, the trip rod 303 strikes the upper end walls of the slots 319^a in the props 319 and quickly elevates the axle 400 to disengage the counters 490 and their drive members. The legs 316 follow the axle, and as soon as the feet 316^a clear the rests 958 1/2, springs 120 385 1/2 draw the legs into line with and over 125 the rests.

Counter detents 414 journaled on a cross rod 404, normally engage the teeth of ratchets 410 fast with the counters to prevent back lash and to retain the counters in their 130

set positions. Springs 480 tend to preserve this engagement.

- The transfer devices for carrying the "tens" from counters of lower denomination to those of next higher denomination comprise rocking levers or carriers 610 journaled on a cross rod 600. Pawls 611 pivoted at 651 to the front rocker arms normally engage the ratchets 410 of the counters 490 to prevent over-rotation thereof. Studs 361 3/4 on the drive members 310 hold the pawls in effective position against the tension of the springs 682 which displace the pawls when the drive members advance, to permit rotation of the counters.

Lugs 610^a on the front rocker arms normally rest upon projections or seats 635 mounted on triggers 612 journaled at their lower ends on a cross rod 600^a, to retain the rockers in their normally set or cocked positions against the tensions of the carrying springs 680 secured to carrying pawls 610 1/2 pivoted at 650 to the rear rocker arms.

When the capacity of a counter is about to be exceeded, that is, when the counter is being turned from 9 to 0, it presses a cam 411 thereon against the free end of its associated trigger to rock the latter against the tension of a restoring spring 681 and release the rocker 610 to the action of the carrying spring, which rocks the front arm of the carrier downwardly to displace the over-rotation preventer pawl 611 and, engages the carrying pawl 610 1/2 with the ratchet 410 of the next counter to the left, to turn the counter forwardly. A tooth 610^b on the rear rocker arm engages between the teeth of the ratchet to limit the rotation imparted thereto by the carrying pawl to one step.

The foregoing construction is old and only constitutes part of the present invention in so far as it is combined with the novel features hereinafter set forth.

In machines which employ transfer or carrying mechanisms operable independently of the counter drive members, of which the Wales is a notable example, the actual addition of "ones" to the counters to the left of those whose capacities have been exceeded, takes place while the counters and drive members are disengaged.

Furthermore, it has been the custom to complete the direct accumulation of amounts on the counters as early as practicable on the return stroke so as to leave as much time as possible during the latter portion of such return stroke, within which to effect the carry, and then, to reset the transfer mechanism at the beginning of the next forward stroke, (which commences a second operation,) in readiness for a possible further carry on the succeeding return stroke (which completes such second operation).

The return of the transfer resetting mech-

anism to normal idle position was coincident with the return of the main drive shaft, and since the normally set transfer devices could be tripped by the counters at any time during the retirement of the drive members, 70 the transfer devices could follow the returning resetting mechanism and engage their carrying pawls 610 1/2 with the ratchets 410 prior to the disengagement of the counters and drive members, although the actual rotation of the counters by the carrying pawls would not occur until the point of such disengagement, but before the counters fully engaged their detents 414.

This style of carry was known to the trade 80 as a "sneak" carry and could only take place between adjacent counters.

It was under the control of the operator in hand-operated machines, and in order to prevent improper manipulation, it 85 was customary to load the carrying springs 680 to insure the proper operation of the transfer devices.

Another style of carry, known as a snap or cross carry, occurs when the counters are 90 substantially in normal disengaged position, at the time when the transfer device is tripped, at which time the transfer resetting mechanism is in idle position, the carrying spring 680 being unrestrained and acting swiftly with its full strength to effect the transfer.

If the counters register 9999.99 for example, and an amount, as "9," is added to the units counter, the transfer from the 100 units to the tens counter would, heretofore, have been of the "sneak" variety, and would take place during the return stroke just as the main shaft was approaching the end of its travel, while the transfer between the 105 tens and hundreds counters, and so on, would be of the "snap" variety and in rapidly successive operations, might take place after the main drive shaft had reached its normal position. Thus, rather nice adjustments were 110 necessary to enable the carrying pawls to properly engage the ratchets 410 when the counters were in at least two positions, and in one of which the counters and ratchets were shifting bodily relatively to the carrying pawls.

By shifting the limits between which a carry or transfer operation is permitted to take place, I have extended or prolonged the time within which a carry can occur, 120 and have greatly improved the operation of the machine, adapted it for more rapid operation, and rendered it more accurate.

To these ends, I lock the transfer devices against effective operation until the counters are completely disengaged from their drive members, and have deferred the actuation of the transfer resetting means from the beginning to the end of the forward stroke, thus eliminating sneak carries and 130

prolonging or extending the time within which "snap" carries may take place.

Although I have chosen to illustrate the invention as applied to the Wales form of carrying mechanism, it is obvious that the broad features of my invention are not restricted thereto.

The form of transfer resetting mechanism illustrated, comprises bell crank levers 615 1/2 (Figs. 1 and 2) journaled on a cross rod 508 1/2. Posts 615 1/2^a projecting upwardly from the arms 615 1/2^b of the levers, support a universal resetting rod 605 which passes through slots 613^a in connecting links 613 pivoted at 650° to the rear arms of the several carriers or rockers 610. Springs 384 normally hold the bell crank levers 615 1/2 and the resetting rod 605 in idle position near the upper ends of the slots 613^a in the connecting links 613, the distance between the resetting rod 605 and the lower ends of the slots 613^a being sufficient to permit the upward thrust of the carrying pawls 610 1/2 under the influence of the carrying springs 680 when the rockers 610 are released for operation.

The actuating means for the resetting mechanism comprises links 615 3/4 pivoted at 655 to the arms 615 1/2 of the bell crank levers and having slots 615 3/4^a in which the trip rod 303 travels, the path of travel of the rod being longer than the slots in the actuating links. Rolls 636 (Fig. 2) on the rod travel in the slots 615 3/4^a to reduce the friction.

Assume that there is an amount registered on the counters, and that the "9" key 190 (Fig. 2) has been depressed to project its stop 115 into the path of its corresponding rack or drive member 310.

Turning the drive shaft 200 forwardly enables the rack to advance as above explained until arrested by its stop.

Meanwhile the draft bars 214 swing the trip rod 303 forwardly, which rod, after lowering the counters 490 until they are supported by the legs 316 on rests 958 1/2, travels idly in the slots 321^a of the trip links 321 and 615 3/4^a of the actuating links 615 3/4. As the main drive shaft approaches the end of its forward stroke, the racks having advanced to their proper positions, the trip rod first engages the forward ends of the slots in the actuating links 615 3/4 to advance the links and rock the resetting levers 615 1/2 which in turn, draw the resetting rod 605 downwardly.

If, on the previous return stroke of the drive shaft, a transfer device has been tripped to effect a carry, the corresponding connecting link 613 will have been raised by the action of the rocker 610 until the lower end wall of its slot 613^a strikes against the normally idle resetting rod 605, as shown in Fig. 4. Consequently, when the

rod 605 is lowered, as in Fig. 2, it pulls the tripped connecting link 613 with it to withdraw the carrying pawl 610 1/2 from the ratchet 410 and elevate the front arm of the rocker until its lug 610^a clears the projection 635 on the trigger 612, whereupon the spring 681 snaps the trigger back into place to position the projection beneath the lug 610^a. Stops 612^a on the triggers strike a stationary part, as the rod 600, to limit the spring-impelled travel of the triggers, when the free ends of the triggers lie in the paths of the tripping cams 411 (Fig. 1). The resetting rod 605 (Fig. 2) rocks the forward arms of the carriers 610 past their normally reset positions to insure the return of the triggers.

If no transfer devices have been tripped on the previous return stroke, the resetting rod 605 at the end of its resetting travel, 75 will contact the lower end walls of the slots in the connecting links to slightly raise the forward ends of the carriers, (Fig. 2).

The drive shaft 200, through the trip rod 303, effects the engagement of the counters and drive members just as the resetting rod 605 reaches the lower ends of the slots 613^a of those transfer devices which remain in set position, and has substantially reset such transfer devices as have been tripped. 95

The space (Fig. 1) left between the resetting rod when at rest, and the bottoms of the slots in links 613, of the set or cocked transfer devices is sufficient to permit an effective operation of the carrying pawl 610 1/2 under the influence of its carrying spring 680 before the links 613 strike the resetting rod, but on its effective travel downwardly, the resetting rod progressively reduces this space until it finally passes the point where an effective carry can be had even if the transfer devices were tripped. 105

Obviously, therefore, any incomplete carries from the previous return stroke, must be completed before the resetting rod reaches this point, as the resetting rod from this point constitutes a lock to prevent carrying operations of the transfer devices. 110

To preserve this lock, I have contrived means to retain the resetting rod in such locking position during the return stroke of the main drive shaft, to prevent an improper control of the carrying action by the operator and to eliminate "sneak" carries, and the consequent necessity for nice adjustments of the transfer devices to effect both sneak and snap carrying operations. 115

To this end, I provide latches 616 journaled on a cross rod 607 and having stepped or graduated shoulders 616^a and 616^b which, by engagement with keepers 615 1/2^c on the resetting levers 615 1/2, hold the levers and the resetting rod 605, in their idle or actuated positions, respectively. Normally, the keepers 615 1/2 engage shoulders 616^a of 120 130

the latches which hold the levers and the resetting rod in idle position against overthrow by springs 384 connected with the levers 615 1/2^c, but as the resetting levers are 5 rocked by the advance of their actuating links 615 3/4 at the end of the forward stroke of the main shaft, the keepers 615 1/2^c swing away from the shoulders 616^a and free the latches to the action of the springs 384 (con- 10 veniently connecting the latches and resetting levers) which snap the shoulders 616^b over the keepers to prevent the restoration of the resetting levers and rod to normal idle positions during the return stroke of 15 the main drive shaft. The levers 615 1/2 and rod 605, therefore, constitute combined transfer resetting and locking mechanism.

The drive shaft 200 on its return stroke, first retires the drive members 310 to directly register on the counters 490, the amount set up on the keyboard. In case the capacity of one of the counters is exceeded in this operation, its cam 411 will wipe past the free end of its trigger 612 to release the transfer device to the action of the spring 680. Should the transfer devices be locked against any movement, at this time, the triggers would spring back to effective positions beneath the front rocker 25 arms and prevent the carry. On the other hand, in the present construction, if a carry was permitted during the engagement of the counters and drive members, it would be rendered ineffective or "swallowed" if an amount was also being registered on the counter onto which the carry was to be 30 made.

It is customary, therefore, to permit a slight preliminary throw of the transfer 40 device sufficient to block the tripped trigger 612 against return, but not sufficient to effect a carrying operation in order that the carry shall not be lost. This I arrange for in my invention as follows:

45 The drive shaft 200 at the end of its forward stroke has rocked the transfer resetting mechanism and transfer devices to the limit of their effective movement in one direction, the keepers 615 1/2^c of the resetting levers swinging some distance below the locking shoulders 616^b of the latches (Fig. 2) extensions of which remain in contact with the keepers to retain the latches and resetting levers in engagement. At the beginning of its return stroke, the shaft 200 shifts the rod 303 backwardly in the slots 615 3/4^a of the actuating links 615 3/4, the trip rod also idly traverses the slots in props 319 and links 321, without restoring said 50 links. As the trip rod recedes from the forward end walls of the actuating links 615 3/4, it frees them to the action of the springs 384 to permit the latter to rock the resetting levers 615 1/2 rearwardly and lift 55 the resetting rod 605 away from the lower

ends of the slots in the connecting links 613, until the keepers 615 1/2^c strike shoulders 616^b on the latches which arrest the resetting rod before it has passed out of locking position relatively to the transfer devices. Incidentally the resetting levers partially retract the actuating links, and the forward edges of the latches 616 overlap the rear ends of the slots 615 3/4^a therein. The resetting rod 605, by this operation permits the carrying springs 680 to tilt the forward arms of the rockers 610 downwardly until their lugs 610^a rest on the projections 635 of the triggers, at which time, the lower ends of the slots 613^a lie below the resetting rod 605. 80 When a trigger is tripped on the return stroke, the spring 680 rocks the rear arm of the transfer device upwardly until the latter is arrested by the contact of the lower end of the slot in the connecting link 613 with the rod 605, and the lug 610^a on the forward arms of the rocker 610 simultaneously shifts downwardly behind the projection 635 on the trigger to hold the latter in idle position. 85

The transfer device is maintained in this position by the latches 616 and resetting rod 605 as the trip rod 303 continues to retrace its path of travel during the return stroke of the drive shaft 200, until the retirement of the drive members 310, whereupon the drive shaft, through the trip rod 303 lifts the props 319 to disengage the counters and drive members. The trip rod or the rollers 636 thereon which traverse the slots in the actuating links 615 3/4, now 100 strike the forward edges of the latches 616 which overlap the rear ends of the slots 615 3/4^a to force their shoulders 616^b off the keepers 615 1/2^c and free the resetting mechanism to the action of its springs 384, which 105 then restore the transfer resetting mechanism to normal idle position where it is held by the engagement of the keepers 615 1/2^c with shoulders 616^b of the latches 616.

The transfer devices which may have been arrested in tripped position are free to operate under practically the full tension of their springs 680 as the resetting rod 605 returns to normal position, and automatically effect snap carries with great speed. The full and dotted line positions of the handle 210 1/2 in Fig. 3 indicate the distance through which the drive shaft rocks from the time when the latches 616 are displaced, to the end of the return stroke. 110 115 120

In case the time interval between the release of the latches 616 near the close of one operation of the machine, and the beginning of the succeeding operation of the machine, is not sufficiently long to complete the carrying action, as might readily happen in rapidly successive repeat operations, for instance, it is plain that the carrying operations may extend throughout nearly the entire time of the succeeding forward stroke, 125 130

or until the transfer resetting mechanism is actuated. This gives a very much longer time within which a carry may take place than heretofore, and practically prevents the possibility of interrupting or cutting off the carrying wave, even in non-commercial examples.

All carrying pawls 610 1/2, being released for operation at a time when the counters 10 are in normal disengaged position or substantially so, strike the counters at practically a constant point in their effective travel, so that adjustments to provide for the engagement of the pawls with the counters when the latter are in one of two or 15 more different positions, are eliminated.

By arranging for the operation of the transfer resetting mechanism at the end of the forward stroke instead of at the commencement thereof, the operation of the machine is made easier, because the parts are under an impetus as the drive shaft nears the end of its forward stroke, and will pick up the slight additional load without the 20 operator being aware thereof.

In order to afford a ready adjustment between the latches 616 and the trip rod 803 to control the time of release of the transfer devices, and also to reduce wear 25 and battering between the latches and the trip rod, I provide each latch with a hardened wear plate 616 1/4 journaled on the rod 607 and adjustably secured to the latch at 655 1/2 to project past the edge thereof and relieve the latch of the wear and impact 30 of the trip rod.

An operation of the machine, referred to in this specification is intended to include one forward and the succeeding return 40 stroke of the drive shaft whether in a circular or an oscillatory direction. In the present machine, the user would rock the main drive shaft forwardly and allow it to return under the power of its spring 285, thus completing a single operation of the 45 machine.

Changes may be made in the form and arrangement of the several parts without departing from the spirit and scope of this 50 invention.

What I claim is:

1. In an adding machine, the combination with counters and drive members adapted for engagement and disengagement; transfer devices; means to latch the transfer devices in set position; means controlled by the counters to trip the latching means, and free the transfer devices for effective operation; and means to reset the transfer devices; of means adapted to coact with the resetting means to cause the latter to hold the transfer devices against complete operation only during the time of engagement of the counters and drive members.

2. In an adding machine adapted for rap-

idly successive operations, the combination with counters and drive members adapted for engagement and disengagement; normally set transfer devices; and means controlled by the counters to trip the transfer devices for effective operation; of combined resetting and locking mechanism for the transfer devices to prevent their operation only during the engagement of the counters and drive members.

3. In an adding machine adapted for rapidly successive operations, the combination with counters and drive members adapted for engagement and disengagement; normally set transfer devices; means controlled by the counters to trip the transfer devices for effective operation; and means to reset the transfer devices, including drive mechanism therefor; of locking mechanism to hold the transfer devices against complete operation; and means to effect the operation of the locking mechanism and the engagement of the counters and drive members substantially simultaneously at the end of the forward stroke in an adding operation.

4. In an adding machine adapted for rapidly successive operations, the combination with counters and drive members adapted for engagement and disengagement; normally set transfer devices; and means controlled by the counters to trip the transfer devices for effective operation; of combined resetting and locking mechanism for the transfer devices; and means to effect the operation of the combined resetting and locking mechanism, and the engagement of the counters and drive members substantially simultaneously.

5. In an adding machine adapted for rapidly successive operations, the combination with counters and drive members adapted for engagement and disengagement; normally set transfer devices; and means controlled by the counters to trip the transfer devices for effective operation; of combined resetting and locking mechanism for the transfer devices; means to effect the operation of the combined resetting and locking mechanism, and the engagement of the counters and drive members substantially simultaneously; and additional locking means to retain the combined resetting and locking means in effective position until the complete disengagement of the counters and drive members.

6. In an adding machine adapted for rapidly successive operations; the combination with counters and drive members adapted for an engagement and disengagement during each normal operation of the machine; normally set transfer devices; and means controlled by the counters to trip the transfer devices; of means to extend the time of effective operation of the transfer devices into the succeeding operation.

7. In an adding machine, the combination with counters and drive members adapted for engagement and disengagement; normally set transfer devices; means controlled by the counters to trip the transfer devices; a drive shaft; and resetting mechanism for the transfer devices; of means connected with the drive shaft to actuate the resetting mechanism just prior to the engagement of the counters and drive members; and means to lock the resetting mechanism in operated position until the disengagement of the counters and drive members is completed. 70
8. In an adding machine, the combination with counters and drive members adapted for engagement and disengagement; normally set transfer devices; means controlled by the counters to trip the transfer devices; a drive shaft; and resetting mechanism for the transfer devices; of means connected with the drive shaft to actuate the resetting mechanism just prior to the engagement of the counters and drive members; means to lock the resetting mechanism in operated position during the engagement of the counters and drive members; and means controlled by the drive shaft to release the locking means after the disengagement of the counters and drive members is completed. 80
9. In an adding machine, the combination with counters; drive mechanism therefor having a forward and a return stroke; normally set transfer devices; and means controlled by the counters to trip the transfer devices on or after the return stroke of the drive mechanism; of resetting mechanism operable as the drive mechanism approaches the end of its subsequent forward stroke. 85
10. In an adding machine, the combination with counters and drive members adapted for engagement and disengagement; normally set transfer devices; triggers to maintain the transfer devices in set position; and means controlled by the counters to trip the triggers of independent locking mechanism for said transfer devices to permit only sufficient operation thereof to lock the triggers in idle position, until after the total disengagement of the counters and drive members. 90
11. In an adding machine, the combination with counters and drive members adapted for engagement and disengagement; normally set transfer devices; means controlled by the counters to trip the transfer devices for effective operation; and a combined resetting and locking mechanism for the transfer devices; of means to delay the operation of the resetting mechanism until immediately prior to the engagement of the counters and drive members; and means to retain the resetting mechanism in operated and locking position until after the disengagement of the counters and drive members. 100
12. In an adding machine, the combination with a main drive shaft having a forward and a return stroke; counters and drive members adapted for engagement and disengagement; normally set transfer devices for the counters; means controlled by the counters to trip the transfer devices for operation; and mechanism to reset the transfer devices; of means to connect the main drive shaft and the resetting mechanism to delay the operation of the resetting mechanism until just before the engagement of the counters and drive members as the main drive shaft approaches the end of its forward stroke. 105
13. In an adding machine, the combination with counters and drive members adapted for engagement and disengagement; means to effect such engagement and disengagement, including a trip rod; normally set transfer devices for the counters; means controlled by the counters to trip the transfer devices; and transfer resetting mechanism operable by the trip rod and relatively to which the trip rod has lost motion; of means to lock the resetting mechanism in operated or set position until the disengagement of the counters and drive members is substantially completed, including an automatically operable latch mounted independently of the resetting mechanism, and controlled by the trip rod. 110
14. In an adding machine, the combination with counters and drive members adapted for engagement and disengagement; normally set transfer devices for the counters; means controlled by the counters to trip the transfer devices for operation; resetting mechanism for the transfer devices; and a common means to control the engagement and disengagement of the counters and drive members and to operate the resetting means; of means to lock the transfer devices in set or cocked position until the disengagement of the counters and drive members is substantially completed, including a latch shiftably supported independently of, and adapted to automatically engage, the resetting mechanism when the latter has cocked the transfer devices, to retain the resetting mechanism and consequently the transfer mechanism in their set positions; said latch being controlled by the means which controls the engagement and disengagement of the counters and drive members. 115
15. In an adding machine, the combination with counters and drive members adapted for engagement and disengagement; a drive shaft to effect such engagement and disengagement; normally set transfer devices for the counters; and means controlled by the counters to trip the transfer devices for effective operation; of resetting mechanism for the transfer devices; and a loose connection between the resetting mechanism and the drive shaft to effect a delay in the operation of the resetting mechanism until 120
16. In an adding machine, the combination with counters and drive members adapted for engagement and disengagement; normally set transfer devices for the counters; means controlled by the counters to trip the transfer devices for effective operation; of resetting mechanism for the transfer devices; and a loose connection between the resetting mechanism and the drive shaft to effect a delay in the operation of the resetting mechanism until 125
17. In an adding machine, the combination with counters and drive members adapted for engagement and disengagement; normally set transfer devices for the counters; means controlled by the counters to trip the transfer devices for effective operation; of resetting mechanism for the transfer devices; and a loose connection between the resetting mechanism and the drive shaft to effect a delay in the operation of the resetting mechanism until 130

just before the engagement of the counters and drive members.

16. In an adding machine, the combination with counters and drive members adapted for engagement and disengagement; a drive shaft having a forward and a return stroke; normally set transfer devices; means controlled by the counters to trip the transfer devices; and resetting mechanism for the transfer devices; of a loose connection between the drive shaft and resetting devices to delay the operation of the resetting devices until the drive shaft has nearly completed its forward stroke.

17. In an adding machine, the combination with counters and drive members adapted for engagement and disengagement; normally set transfer devices for the counters; means controlled by the counters to trip the transfer devices; resetting mechanism for the transfer devices; and means to actuate the resetting mechanism; of a latch supported independently of the resetting mechanism, and adapted to automatically engage the resetting mechanism only when the latter has been shifted to its active position, to lock the resetting mechanism in active position and the transfer devices in cocked or set position, during the period of engagement of the drive members and counters, and thus prevent an effective operation of the transfer devices; said actuating means for the resetting mechanism adapted to contact and displace the latch only after the counters have been disengaged from their drive members, to enable the transfer devices to operate the counters at substantially the same relative point on each transferring operation, the carry resetting mechanism adapted to retain the latch in idle position, substantially throughout the entire period of disengagement of the counters and drive members, to permit carrying operations to occur.

18. In an adding machine, the combination with counters and drive members adapted for engagement and disengagement; the counters normally being disengaged from the drive members; a drive shaft; means controlled by the drive shaft to engage and disengage the counters and drive members; normally set transfer devices for the counters; and means controlled by the counters to trip the transfer devices; of resetting mechanism for the transfer devices, including actuating means connected with the drive shaft for operation just prior to the engagement of the counters and drive members, to actuate the resetting mechanism; and latches to detain the resetting mechanism in operated position; the actuating mechanism adapted to release the latches upon the return of the counters to normal position.

19. In an adding machine, the combina-

tion with counters and drive members adapted for engagement and disengagement; a drive shaft; means controlled by the drive shaft to engage and disengage the counters and drive members; normally set transfer devices for the counters; and means controlled by the counters to trip the transfer devices; of resetting mechanism for the transfer devices, including actuating means connected with the drive shaft and operated thereby just prior to the engagement of the counters and drive members to actuate the resetting mechanism; and latches to detain the resetting mechanism in operated position; the actuating mechanism adapted to release the latches at a predetermined point in its stroke after the disengagement of the counters and drive members.

20. In an adding machine, the combination with counters and drive members adapted for engagement and disengagement; normally set transfer devices for the counters; and means controlled by the counters to trip the transfer devices for operation; of resetting mechanism for the transfer devices, including levers operatively connected with the transfer devices; slotted links connected with the levers; and a power member shiftable in the slots and having a path of travel of greater length than the slots.

21. In an adding machine, the combination with counters and drive members adapted for engagement and disengagement; normally set transfer devices for the counters; means controlled by the counters to trip the transfer devices for operation; and resetting mechanism for the transfer devices, including levers; and means to connect the levers and the respective transfer devices; of an actuating member having a forward and a return stroke, to rock the levers at the end of its forward stroke to reset the transfer devices; a latch to automatically lock the resetting mechanism in active position and the transfer devices in cocked or set position; said actuating means also operable to effect the engagement and disengagement of the counters and drive members, and to disable the latch at the end of its return stroke, to free the transfer devices for operation.

22. In an adding machine, the combination with counters and drive members adapted for engagement and disengagement; normally set transfer devices for the counters; and means controlled by the counters to trip the transfer devices for operation; of resetting mechanism for the transfer devices, including levers operatively connected with the transfer devices; reciprocating means arranged to rock the levers at the end of its effective stroke, to reset the transfer devices; and releasable means to automatically lock the levers in

operated position, said reciprocating means adapted to disable the lever-locking means, on its return stroke.

23. In an adding machine, the combination with counters and drive members adapted for engagement and disengagement; normally set transfer devices for the counters; and means controlled by the counters to trip the transfer devices for operation; of resetting mechanism for the transfer devices, including bell crank levers loosely connected with the transfer devices; keepers on said levers; slotted links connected to the levers to rock the latter; actuating means traversing the slots in the links and having a path of travel longer than the slots; spring latches to engage the keepers to hold the levers in operated position and prevent the operation of the transfer devices for carrying; said actuating means adapted to release the latches on its return to normal idle position.

24. In an adding machine, the combination with counters and drive members adapted for engagement and disengagement; normally set transfer devices for the counters; and means controlled by the counters to trip the transfer devices for operation; of resetting members operatively connected with the transfer devices; actuating means to operate the resetting members, at the end of its forward stroke; restoring means for the resetting members; and latches to detain the resetting members in actuated position to lock the transfer devices against a carrying operation during the return of the actuating means; said actuating means adapted to displace the latches at the end of its return stroke.

25. In an adding machine, the combination with counters and drive members adapted for engagement and disengagement; a drive shaft to control such engagement and disengagement; normally set transfer devices for the counters; and means controlled by the counters to trip the transfer devices for operation; of resetting mechanism operatively connected with the transfer devices; actuating means for said resetting mechanism, and connected with the main drive shaft for operation; latches to detain the resetting mechanism in operated position during the engagement of the counters and drive members, said latches, when effective, lying in the path of the actuating means to be displaced thereby after the disengagement of the counters and drive members, and means to restore the resetting mechanism.

26. In an adding machine, the combination with counters and drive members adapted for engagement and disengagement; a drive shaft to control such engagement and disengagement; normally set transfer devices for the counters; and means

controlled by the counters to trip the transfer devices for operation; of resetting mechanism operatively connected with the transfer devices; actuating means for said resetting mechanism, and connected with the main drive shaft for operation; latches to detain the resetting mechanism in operated position during the engagement of the counters and drive members, said latches, when effective, lying in the path of the actuating means to be displaced thereby after the disengagement of the counters and drive members; and means tensioned by the displacement of the latches to restore the resetting mechanism.

27. In an adding machine, the combination with counters and drive members adapted for engagement and disengagement; a drive shaft to control such engagement and disengagement; normally set transfer devices for the counters; and means controlled by the counters to trip the transfer devices for operation; of resetting mechanism operatively connected with the transfer devices; actuating means for said resetting mechanism, and including slotted links; actuating means traversing the slots in the links and connected with the main drive shaft to have a path of travel longer than the slots; and latches to detain the resetting mechanism in operated position; said latches, when effective, overlapping the slots in position to be displaced by the actuating means.

28. In an adding machine, the combination with counters and drive members adapted to be engaged and disengaged; a drive shaft to control such engagement and disengagement; normally set transfer devices for the counters; and means controlled by the counters to trip the transfer devices; of resetting members operatively connected with the transfer devices; restoring means for the resetting members; keepers on said resetting members; actuating means for the resetting members, and connected with the drive shaft for operation; and stepped latches, one of the steps of each of which normally lies in engagement with the keepers to arrest the resetting members in normal position against the action of the restoring means; another of the steps adapted to engage the keepers when the resetting members are in actuated position, to lock the transfer devices against operation; said actuating means adapted to displace the latches to release the resetting members for restoration to normal position.

29. In an adding machine adapted for rapidly successive operations, the combination with counters and drive members adapted for engagement and disengagement; normally set transfer devices; and means controlled by the counters to trip the transfer devices for effective operation; of locking

means for the transfer resetting mechanism effective during the engagement of the counters and drive members; and means to first disengage the counters and drive members, 5 and then disable the locking means.

30. In an adding machine adapted for rapidly successive operations, the combination with counters and drive members adapted for engagement and disengagement; normally set transfer devices independent of the drive members; and means controlled by the counters to trip the transfer devices for effective operation; of means to utilize substantially the entire period of time during 10 which the counters and drive members are disengaged in successive operations of the machine, within which the transfer devices may function in carrying operations.

31. In an adding machine, the combination 15 with counters and drive members adapted for engagement and disengagement; normally set transfer devices; means controlled by the counters to trip the transfer devices; transfer resetting mechanism; and drive means therefor, which means is also effective to engage and disengage the counters and drive members; of locking mechanism supported independently of, and automatically operable upon the transfer resetting mechanism 20 after the latter has been actuated by the drive means to reset the transfer devices, to hold the transfer devices against complete operation; said locking mechanism being released by the drive means on its return to normal position, to free the transfer devices 25 for operation at a constant and predetermined period in the operation of the machine.

32. In an adding machine, the combination 30 with counters and drive members adapted for engagement and disengagement; normally set transfer devices; means controlled by the counters to trip the transfer devices; a drive shaft; and resetting mechanism for 35 the transfer devices; of means connected with the drive shaft to actuate the resetting mechanism just prior to the engagement of the counters and drive members; and auxiliary means to lock the resetting mechanism 40 in substantially operated position until the disengagement of the counters and drive members is completed.

33. In an adding machine, the combination 45 with counters and drive members adapted for engagement and disengagement; normally set transfer devices; means controlled

by the counters to trip the transfer devices; a drive shaft; and resetting mechanism for the transfer devices; of means connected with the drive shaft to actuate the resetting 60 mechanism just prior to the engagement of the counters and drive members; means to automatically lock the resetting mechanism in substantially operated position during the engagement of the counters and drive members; and auxiliary means controlled by the drive shaft to release the locking means 65 after the disengagement of the counters and drive members is completed.

34. In an adding machine, a main drive 70 shaft, the cycle of operation of which comprises a forward and a return stroke; counters and drive members adapted for engagement at the end of the forward stroke and disengagement at the end of the return 75 stroke; transfer devices; means to latch the transfer devices in set position; means controlled by the counters to trip the latching means and free the transfer devices for operation; and a resetting bail for the transfer 80 devices operable by the main drive shaft; of connections between the main drive shaft and the resetting means to delay the effective operation of the resetting means until approximately the end of the forward stroke 85 of the main drive shaft and substantially at the moment of engagement of the counters and drive members; and means to lock the resetting means in operated position and thereby prevent operation of the transfer 90 devices, said locking means releasable by the main shaft immediately subsequent to the disengagement of the counters and drive members.

35. In an adding machine, the combination 95 with counters and drive members adapted for engagement and disengagement; transfer devices; means to latch the transfer devices in set position; means controlled by the counters to trip the latching means and free the transfer devices for effective operation; and means to reset the transfer devices; of locking means to automatically retain the resetting means in operated position 100 to thereby lock the transfer devices against effective operation during the engagement of the counters and drive members, said locking means being rendered ineffective to lock the transfer devices against operation so long as the counters and their drive members remain disengaged.

ARTHUR PENTECOST.
